(57) **CLAIM**

The ornamental design for a cargo netting, as shown and described.

DESCRIPTION

FIG. 1 is a top plan view of a cargo netting;

FIG. 2 is a front top-side perspective view thereof;

FIG. 3 is a rear top-side perspective view thereof;

FIG. 4 is a bottom plan view thereof;

FIG. 5 is a front bottom-side perspective view thereof; and,

FIG. 6 is a rear bottom-side perspective view thereof.

The broken line showing electronic components is included for the purpose of illustrating environmental structure and forms no part of the claimed design.
